ANTIDRIFT LOCK FOR RADIO CONTROL

Raymond B. Meyer and Corrie F. Rudolph,
Washington, D. C.

Application August 14, 1935, Serial No. 36,166

6 Claims. (Cl. 188—74)

(Granted under the act of March 3, 1883, as
amended April 30, 1928; 370 O. G. 757)

This invention relates to an antidrift lock for a radio control and has for an object to provide an improved means for holding the control shaft in a radio set against undesired rotation, thus preventing the tuning of the circuit from being disturbed.

It is the usual practice to adjust the various circuits of a radio transmitter or radio receiver by means of controls connected in some manner to variable capacitors or variable inductors. These controls usually terminate in a crank handle or a knob on the end of a shaft extending through the front panel of the radio set. A crank is the most desirable form of control means where speed and ease of operation are desired. This form of control, however, includes a certain amount of unbalanced weight connected with the control shaft and thus, when the crank is brought to rest in any position other than vertical, vibration or jarring will cause the crank to move, thus destroying the tuning of the circuit in question. This is especially true when the radio is on board an airplane or a vessel where the use of a crank or arm on the control shaft is most desirable. In order to overcome this difficulty this invention provides a locking device on the control shaft to prevent such undesired drift or rotation.

The device consists essentially of a tapered, threaded bushing encompassing the control shaft and affixed to the radio panel, the bushing having over it a large knurled nut. The bushing is slotted beyond the radio panel and is provided with a tapered thread so that as the nut is moved from one end to the other, the bushing is constricted to grip the shaft and prevent its rotation. Thus, a well distributed pressure and friction is provided on the shaft, holding it at any angle at which it may be set.

With the foregoing and other objects in view, as will hereinafter become apparent, this invention comprises the construction, combination and arrangement of parts hereinafter disclosed, claimed and illustrated on the accompanying drawing, wherein,

Fig. 1 is a sectional view of the invention as applied to a control shaft of a radio set, and

Fig. 2 is a perspective partly sectional view of the invention disassociated from the radio set.

There is shown at 10 the antidrift lock of this invention, which is affixed to the front panel 11 of a radio set 15. The lock includes a bushing affixed in the same aperture in panel 11 through which the radio control shaft 12 extends. To one end of this control shaft 12 is affixed a crank 13

having a handle or knob 14. The end 16 of the bushing is affixed to the panel 11 against rotation by any suitable means such as welding or brazing or by the pin 17 extending into the panel. The other end of this bushing is provided with a plurality of longitudinal slots 18 and the external surface of the bushing throughout the slotted portion is provided with a tapered thread 19 about which is placed the nut 20, knurled as at 21, for ease in manipulation. The end of the threaded portion 19 may be provided with a retaining ring 22 to prevent accidental loss or removal of the nut 20.

In operation, the normal unconstricted diameter of the bushing is such that the shaft 12 may be rotated freely therein and in this position the crank or arm 13 is manipulated by means of the knob 14, to properly tune the radio 15. When the radio has been properly tuned, the nut 20 is tightened on the bushing 19 by rotating it about the tapered thread 19 towards the enlarged end thereof, thereby causing the bushing to constrict and grip the radio shaft 12, which passes therethrough. The shaft 12 is thus locked against undesired rotation, being gripped with a well distributed friction or pressure thereabout. When desired to re-tune the radio it is only necessary to loosen the nut 20, permitting the shaft to be turned by means of a crank arm 13 and handle knob 14.

The invention herein described may be manufactured and used by or for the Government of the United States of America for governmental purposes without the payment of any royalties thereon.

What is claimed is:

1. An antidrift lock for the control shaft of a radio set wherein the control shaft has an off-center weight for easy manipulation thereof, said antidrift lock comprising a constrictable bushing encompassing the control shaft and affixed to the radio set panel, said constrictable bushing being longitudinally slotted and provided with a tapered thread therein, said means for constricting the bushing comprising a knurled nut adapted to be operated along the tapered thread.
2. An antidrift lock for the control shaft of a radio set wherein the control shaft has an off-center weight for easy manipulation thereof, said antidrift lock comprising a constrictable bushing encompassing the control shaft and affixed to the radio set panel, said constrictable bushing being longitudinally slotted and provided with a tapered thread therein, said means for constricting the bushing comprising a knurled nut adapted to be operated along the tapered thread.
3. An antidrift lock for the control shaft of a radio set wherein the control shaft has an off-center weight for easy manipulation thereof, said

- antidrift lock comprising a constrictable bushing encompassing the control shaft and affixed to the radio set panel, and means for constricting said bushing on the shaft to prevent rotation thereof.
- 5 4. An antidrift lock for the control shaft of a radio set wherein the control shaft has an off-center-weighted crank arm for easy manipulation thereof, said antidrift lock comprising a constrictable bushing encompassing the control shaft and affixed to the radio set panel, and means for constricting said bushing on the shaft to prevent rotation thereof, said constrictable bushing being longitudinally slotted and provided with a tapered thread therein, said means for constricting the bushing comprising a knurled nut adapted to be operated along the tapered thread.
- 10 5. An antidrift lock for the control shaft of a radio set wherein the control shaft has an off-center-weighted crank arm for easy manipulation thereof, said antidrift lock comprising a constrictable bushing encompassing the control shaft and affixed to the radio set panel, and means for constricting said bushing on the shaft to pre-
- 15 vent rotation thereof, said constrictable bushing being longitudinally slotted and provided with a tapered thread therein, said means for constricting the bushing comprising a knurled nut adapted to be operated along the tapered thread, and a 5 retaining ring on the end of the tapered bushing preventing accidental displacement of the constricting nut.
6. An antidrift lock for the control shaft of a radio set which control shaft has a crank arm for 10 easy manipulation thereof, said antidrift lock comprising constrictable bushing having a normal unconstricted diameter at least as large as the diameter of the radio control shaft, one end of said bushing being affixed to the radio set, the 15 other end of said bushing being provided with a tapered thread and being longitudinally slotted to permit it to be constricted, and means for constricting said slotted end of said bushing comprising a nut adapted to be manipulated along 20 said tapered thread.
